J. B. NEFF,
Sulky-Plow.

No. 224,035.

Patented Feb. 3, 1880.

Witnesses:

Inventor:

UNITED STATES PATENT OFFICE.

JOSEPH B. NEFF, OF CUBA, ASSIGNOR TO REUBEN ELWOOD, OF SYCAMORE, ILLINOIS.

SULKY-PLOW.

SPECIFICATION forming part of Letters Patent No. 224,035, dated February 3, 1880.

Application filed December 16, 1878.

To all whom it may concern:

Be it known that I, JOSEPH B. NEFF, of Cuba, Fulton county, State of Illinois, have invented new and useful Improvements in Sulky-Plows, of which the following is a full description, reference being had to the accompanying drawings, in which—

Figure 1 is a plan view; Fig. 2, a side elevation; Fig. 4, an enlarged detail of the lever-connection; Fig. 5, a cross-section on line $\alpha\alpha$ of Fig. 2, enlarged; and Fig. 3, a modification of the lever attachment.

The object of this invention is to provide the plow of a sulky-plow with a limited free vertical movement through or by the hand-lever connection, and to improve the details of construction; and its nature consists in providing devices for regulating the direction and play of the tongue or guide-pole.

In the drawings, A indicates a bent axle or main frame; B, wheel spindles or axles; C, a bent or cranked rock-shaft; C', a coupling for connecting the plow-beam with the rock-shaft; D, the plow-beam; E, a bar to which the tongue is attached; F, tongue or guide-pole; G, hand-lever; H, a notched segment or curved rack; I, a crank-head for connecting the hand-lever with the rock-shaft; J, brace-bars for connecting the frame or bent axle with the plow-beam near its front end; K, a brace connecting the bar E with the opposite side of the frame; a, a bracket or socket for the rear end of the tongue; a', a slot through its bottom; b, a plate or cross-bar located beneath the bracket a; c, bolts; e, an inverted stirrup; f, slots near its ends; g, a collar with set-screw for adjusting and holding the coupling C' in place; h, lever and rod for operating the pawl of the lever G, and i a groove or slot in the crank-head.

The bar or beam E and the tongue or guide-pole F are made of wood, and the other parts are, by preference, made of iron. The bent axle or frame A is made of flat bar-iron, and is bent up sufficiently far to permit the raising of the plow up out of the ground.

The spindle B and the braces J K are permanently attached to the part A. The oppo-

site spindle (not shown) is to be adjustably attached by any suitable or well-known means. 50

The plow-beam D is pivoted to the front end of the brace-bars J, so that it may turn between them. The bent rock-shaft C is journaled to or through the bent axle A, and its projecting end is provided with a crank or lever head, I, which has its face provided with a slot or opening, i, formed, as shown at Fig. 4, so as to give the rock-shaft C a limited free play on the lower end of the hand-lever. By this arrangement the shaft C can rock or play 60 freely on the hand-lever when locked within the limits of the opening i, which movement permits the plow to rise and fall when the hand-lever is locked without lifting or depressing any portion of the frame-work. The shaft 65 C can be rocked to any desired position by continuing the movement of the hand-lever after the limit of free play has been reached, and by continuing it far enough the plow is raised and may be held out of the ground. 70

In the modification shown at Fig. 3 the lever G is carried forward and pivoted to the bar E, and its lower end connected with the crank or lever head I by means of a link, I', and in this change it will be found more convenient 75 to make the slot i in the link, which allows the same free play to the rock-shaft and the rising and falling of the plow as that given by the slot i in the head shown at Fig. 4. This modification can be carried to the rear of the 80 axle instead of the front, and the link I' may be pivoted to the hand-lever above its pivot, as well as below.

The plow-beam is connected with the rock-shaft by means of two hangers encircling the 85 shaft and turning upon it, and they are pivoted to the plow-beam. They are adjusted along the shaft and kept in place by the collar and set-screw g. At the rear end of the tongue there is placed on the bar E a plate, b, through 90 which the bolt e passes. Its face is serrated or roughened to engage with corresponding serrations or roughenings on the bottom of the bracket a. The bracket a is provided with a bolt, d, for holding the rear end of the tongue 95 F, and it is provided with a slot, a', through

which the bolt *c* passes. By this arrangement the rear end of the tongue can be shifted laterally in either direction, and when adjusted it is locked in place by the bolt *c*.

5 The inverted stirrup *e* at the front end of the bar *E* acts as a pivot in shifting the line of the tongue. It also limits the up-and-down movement of the tongue, and prevents the mounted frame from tipping forward. This 10 stirrup is made adjustable in height by means of the slots *f* and the bolt passing through them, there being on the opposite side a slot corresponding to the one shown at *f*, Fig. 2.

A clevis, driver's seat, foot-board, wheels, 15 leveling devices, and a plow are to be applied. They may be of any well-known construction, and suitable ones are shown in another application made by me of even date herewith.

The bars *J* are pivoted to the axle or frame 20 *A*, and also to the plow-beam *D*, which permits an easy vertical movement at the front end

while it is guided sidewise. By attaching the plow-beam in this manner the free play of the rock-shaft is not confined to the plow, as it would be, in the main, if the arms were rigid, 25 and by changing the position of the rock-shaft the front end of the beam can be elevated or depressed so as to change or gage the running depth of the plow without changing the position of the frame or making the connection 30 rigid.

What I claim as new, and desire to secure by Letters Patent, is—

In combination with the pivoted tongue *F*, the adjustable inverted stirrup *e*, and slotted 35 bracket *a*, the pivotal bolt *d*, serrated plate *b*, and bolt *c*, substantially as shown and described.

JOSEPH B. NEFF.
